UNITED STATES PATENT OFFICE.

HOWARD H. CHRISTENSEN, OF CHICAGO, ILLINOIS, ASSIGNOR TO CHARLES A. DREIER,
OF CHICAGO, ILLINOIS.

TOOL FOR RECUTTING VALVE-SEATS.

1,271,854.

Specification of Letters Patent.

Patented July 9, 1918.

Application filed February 10, 1917. Serial No. 147,925.

To all whom it may concern:

Be it known that I, HOWARD H. CHRISTENSEN, a citizen of the United States, residing at Chicago, in the county of Cook and State 5 of Illinois, have invented certain new and useful Improvements in Tools for Recutting Valve-Seats, of which the following is a specification.

The present invention relates to a tool for 10 recutting the flat valve seats such as are found in faucets used in connection with bath-tubs, wash-bowls, etc.

The principal objects of the invention are, 15 to produce a tool of the character specified which is cheap and simple of operation, which can be readily and quickly fixed in position to the faucet body; which is adaptable for use with various sized faucets; and which will have means for exerting a positive 20 downward feeding action upon the cutting tool to keep it in position upon the valve seat.

Further objects of the invention are, to 25 provide means for centering the tool during the valve cutting operation; to arrange the mounting for the tool so that the tool is freely revoluble therein; and to arrange the cutting member of the tool so that it can be used either as a cutter or reamer.

30 The invention further consists in the features of construction and combination of parts hereinafter described and claimed.

In the drawings:

Figure 1 is a longitudinal section through 35 the tool of the present invention;

Fig. 2, a perspective detail of the cutting implement;

Fig. 3, a cross-section of the cutting implement, showing the centering plug 40 moved and positioned below;

Fig. 4, a detail of a part of the appliance for securing the tool to the faucet body; and

Fig. 5, an elevation of one of the members 45 employed for feeding the tool during the cutting operation.

In the art to which the present invention relates, there is a certain flat valve seat in the construction of faucets, upon which a disk washer is seated. It is necessary to the 50 proper operation of the faucet that this seat be kept in true condition to receive the washer, and from time to time the seat must be recut to maintain it flat.

In the present invention, in addition to 55 other alleged novel features, mechanical means are provided, which can be quickly

and easily operated, to maintain mechanically the downward pressure upon the cutting tool, thus eliminating the exertion of direct pressure on the tool by the user, and 60 only requiring upon the part of the user, the necessary power to turn the tool. This renders the tool more easily operated because of the fact that the operator is not required to manually place the pressure on the 65 tool necessary to keep it in cutting engagement.

Referring now to the drawings, the device is shown in connection with a faucet body 6, which may be of any suitable style and 70 size; and in the interior of this body is a flat valve seat 7, which is the one upon which the cutting tool is to operate. The cutting tool consists of a rod 8, the lower end of which is adapted to be threaded or otherwise 75 connected to a cutting member 9. This cutting member, in the form shown, has horizontally disposed teeth 10 formed upon one surface for cutting the valve seat 7 flat. The body of the tool is of tapering formation, 80 as shown, and is further provided with vertically extending teeth 11, whereby this portion of the tool can serve as a reamer.

With the tool in the position of Fig. 1, the horizontal teeth 10 are brought into play, 85 and it is being used as a valve seat cutter. If turned end for end, then the small portion of the body would be downward, the vertical teeth would be in operative position, and it could be used as a reamer. 90

A plug 12 is provided, adapted to be attached to the tool and serve as a centering member therefor. The tool is provided with two threaded openings 13, so as to enable a reversal when it is desired to change from a 95 valve cutter to a reamer, or vice versa.

The rod 8 of the tool is supported by means of a holder, which will be given the general numeral 14. This holder consists of a part 15 for affixing it to the body of the 100 faucet, a part 16, which is adapted to manipulate the part 15 to force it in place, and a part 17, which has to do with the mechanical maintaining of downward pressure on the tool. 105

The part 15 comprises a body 18 of rubber or other compressible substance. Extending through this rubber is a sleeve 19 formed with a flange 20 on its lower end, which sleeve for clearness will be termed the lower 110 exteriorly threaded sleeve. The upper end of the sleeve is exteriorly threaded as at 21

and is formed with a groove 22, which receives a prong or projection 23 on a holder 24. Adapted to be advanced over the threaded portion 21 of the sleeve 19 is a sleeve 25, terminating in a hand grip 26, which sleeve 25 for clearness will be termed the intermediate, interiorly threaded sleeve.

In operation, the member 15 is placed in position with the compressible body 18 in the open upper end of the faucet body. The hand grip 26 is manipulated by the operator to turn the sleeve 25, which will draw the sleeve 19 upward, so that the flange 20 will engage with the lower face of the compressible body. The holder 24 has been previously placed in position, and the operator, by grasping the finger-piece 27 of the holder 24, will prevent the sleeve 19 from turning as the handle 26 is rotated. This will insure the sleeve 19 being drawn upward as the handle is turned. The holder will press against the upper portion of the compressible body and will be held against upward movement by the end of the sleeve 25. Thus, the compressible body 18 will be positioned between the holder 24, which is held against upward movement, and the flange 20, which is advanced upwardly by the movement of the sleeve 19. The compressible body will thus be compressed and expanded horizontally and brought firmly against the inner walls of the open end of the faucet body, so that it is held securely in place.

The interior face of the sleeve 25 contains a threaded surface 28, which receives the threads upon a sleeve 29 attached by ribs 30, or otherwise, to a disk-like member 31, which sleeve 29 for clearness will be termed the upper, exteriorly threaded sleeve. This disk-like member forms a hand grip and preferably has a knurled face, as in Fig. 5, and is provided with a central opening 32, through which extends a sleeve 33 having a lower head 34 and a nut 35 on its upper end. The sleeve 29, ribs 30, and disk-like member 31 constitute a chambered member, which is the part 17 heretofore referred to. The lower head 34 rests inside of the chambered member, and when the tool is operated, said head is brought into abutting engagement with the under face of the disk-like member 31 to obtain downward pressure on the tool. The sleeve 33 is threaded upon a threaded surface 36 upon the upper end of the rod 8, and upon the extreme upper end of the rod is a hand-grip 37.

The operation is as follows:

The parts 17, 16, and 15, together with the rod 8 and operating member 9, are first assembled together and the tool placed in position with respect to the faucet. The compressible body 18 is then expanded and the holder portion secured in place at the upper end of the faucet body. The tool is then lowered within the valve body until the acting

surface of the cutting member rests upon the valve seat. Then, by a manipulation of the member 17, or of the sleeve 33, the said member and sleeve are brought into a position where the head 34 will engage with the under face of the disk 31. Then, by grasping the hand grip 31 the operator can rotate the member 17, which will advance downward by reason of its threaded engagement between the upper sleeve 29 and the intermediate sleeve 22, and such downward travel will exert pressure on the head 34 and sleeve 33, which latter is connected to the rod 8, and thus a downward pressure is exerted on said rod. This downward pressure will bring the cutting member 9 into hard engagement with the valve seat, to carry on the cutting operation. The screw threads on the sleeve 33 and rod 8 are formed to have a good tight fit, which will be sufficient to overcome the friction when the ring 31 and head 34 contact, thus allowing sleeve 33 to revolve freely with the rod 8, whereby there will be no feeding downward of the stem 8 by reason of a relative rotative movement between the said stem and the sleeve 33.

In this manner the cutting end of the tool can be kept in firm engagement with the work by simply manipulating the hand grip 31, and the hand of the operator need only be used for turning the rod 8 through the hand-grip 37, and no downward pressure on this hand-grip need be exerted. In this way the tool can be readily operated, even under adverse circumstances.

It is to be noted that the rod 8 at all times has a free turning movement in the holder, although the holder exerts the necessary downward pressure for the cutting.

The parts 15, 16 and 17 give an elongated bearing for the rod 8, which is disposed longitudinally of said rod, thereby preventing the rod from getting out of a straight up and down position during the cutting operation. This is important, because the rod, if slanted, would position the cutting tool crooked and cause an uneven cutting.

I claim:

1. In a tool for recutting valve seats, the combination of a cutting member, a rod attached to said member, a holder for the rod in which it has a free rotative movement, a plug of expansible and yieldable material arranged to be inserted upon the inside of the open upper end of the valve casing, means forming a part of said holder for expanding said plug to bring it into engagement with the inner wall of said upper end of the valve casing to lock the holder in place, and means forming a part of said holder and adapted by adjustment to mechanically exert a downward pressure on the rod to feed the cutting member into cutting position, substantially as described.

2. In a tool for recutting valve seats, the

combination of a cutting member, a rod attached to said member, a holder for the rod in which it has a free rotative movement, an expansible and yieldable member forming a part of said holder and adapted to be inserted in the inside of the open upper end of the valve casing, a movable sleeve forming a part of said holder and extending through said expansible member and underlying one side thereof, means for moving said sleeve to draw it into tight engagement with said expansible member, means for preventing movement of the expansible member out of position whereby it is expanded by the pressure of said sleeve and brought into engagement with the inner wall of said upper end of the valve casing to lock the holder in place, and means associated with said holder and adapted by adjustment to mechanically exert a downward pressure on the rod to feed the cutting member into cutting position, substantially as described.

3. In a tool for recutting valve seats, the combination of a cutting member, a rod attached to said member, a holder for the rod in which it has free rotative movement, said holder comprising lower, intermediate and upper sleeve members all arranged concentric with the rod and providing an elongated bearing for the rod, in which the rod has a free turning movement, expansible means associated with the lower sleeve, a threaded connection between the lower and intermediate sleeves whereby when said intermediate sleeve is rotated, said lower sleeve is moved to expand said expansible means and lock the holder in place upon the valve casing, a threaded connection between the upper and intermediate sleeve, a head on the rod, a head connected to the intermediate sleeve, and said heads when brought into contact placing a downward feeding pressure on the rod, substantially as described.

4. In a tool for recutting valve seats, the combination of a cutting member, a rod attached to said member, a holder for the rod in which it has free rotative movement, said holder comprising lower, intermediate and upper sleeve members all arranged concentric with the rod and providing an elongated bearing for the rod, in which the rod has a free turning movement, expansible means associated with the lower sleeve, a threaded connection between the lower and intermediate sleeves whereby when said intermediate sleeve is rotated, said lower sleeve is moved to expand said expansible means and lock the holder in place upon the valve casing, a holder member engaging with the lower sleeve to prevent turning of said

sleeve when the intermediate sleeve is rotated, a threaded connection between the upper and intermediate sleeve, a head on the rod, a head connected to the intermediate sleeve, and said heads when brought into contact placing a downward feeding pressure on the rod, substantially as described.

5. In a recutting tool for valve seats, the combination of a cutting member, a rod secured to said member, a holder for the rod comprising lower, intermediate and upper sleeves arranged concentric with the rod and forming an elongated bearing therefor, in which the rod has a free turning movement, expansible means carried by the lower sleeve, a threaded surface on the exterior of the upper part of the lower sleeve, an interior threaded surface on the lower and upper parts of the intermediate sleeve, with the threaded surface on the lower sleeve meshing with the lower threaded surface on the intermediate sleeve, an exterior threaded surface on the upper sleeve meshing with the upper threaded surface on the intermediate sleeve, a head attached to the upper sleeve, a head attached to the rod, said intermediate sleeve when rotated moving the lower sleeve through the threaded engagement therewith to expand the expansible means and secure the holder to the valve, said upper sleeve when rotated moving with respect to the intermediate sleeve by the threaded connection therewith and bringing the head on the upper sleeve into engagement with the head on the stem to exert a downward feeding pressure on the rod, substantially as described.

6. In a tool for recutting valve seats, the combination of a cutting member, a rod secured to the cutting member, lower, intermediate and upper sleeves arranged concentric with the rod and forming an elongated bearing for the rod, in which it has a turning fit, expansible means carried by the lower sleeve, a threaded connection between the lower and intermediate sleeves, a hand grip on the intermediate sleeve to permit turning thereof, whereby the lower sleeve is moved to expand the expansible means and lock the tool to the valve casing, a threaded connection between the intermediate and upper sleeves, a hand grip connected to the upper sleeve and constituting a head, a head on the valve stem, and said upper sleeve when turned moving on the threaded surface of the intermediate sleeve to bring the said heads into contact and exert a downward feeding pressure on the rod, substantially as described.
